UNITED STATES PATENT OFFICE.

ARTHUR G. L. NEIGHBOUR, OF BRIGHTON, VICTORIA, AUSTRALIA.

FLUID PUMP AND COMPRESSOR.

Application filed December 23, 1920. Serial No. 432,842.

To all whom it may concern:

- Be it known that I, ARTHUR GEORGE LLOYD NEIGHBOUR, a subject of the King of Great Britain, residing at Brighton, in the 5 State of Victoria, Commonwealth of Australia, have invented new and useful Improvements in and Relating to Fluid Pumps and Compressors, of which the following is a specification.
- 10 This invention relates to improvements in pumps and compressors of that type wherein in the operative piston or plunger is furnished with a transverse guide-way in which is slidably fitted a cross-head or die-block 15 rotatably mounted on a crank-shaft arranged in a plane at right angles to the axis of the piston. Rotary motion of the crank-shaft effects endwise movements of the piston or plunger by means of the cross-head or die-block and the latter is caused by 20 the transverse guide-way to reciprocate axially therein.
- In prior machines of this character, there 25 has been employed a piston or plunger which was provided with a slotted or bored guide-way having a lateral opening at the side on which the operative shaft was located. This lateral opening was provided to accommodate the crank-pin and it extended 30 from end to end of the guide-way. The metal on one side of the guide-way was in this manner completely removed, while the metal on the other side of the guide-way alone served to connect together the opposite ends of the piston or plunger. Pistons or plungers of this construction were necessarily weak, especially when made of considerable size and of cast metal, and although serviceable for small pumps they 35 have proved to be unsuitable in their application to pumps having cylinders, the diameters of which exceeded moderate dimensions.
- Moreover, in the constructions referred to, the pistons have been cut away to provide 40 clearance for the crank arms, or the latter have been arranged in recesses formed in the cylinders, thus necessitating the use of overhung crank pins of undue length.
- Furthermore, in prior constructions the 45 operative crank-shaft has been supported on and extended laterally from one side only of the pump or compressor and the crank employed has been of overhung design.
- 50 Salient features of the present invention 55 reside in the provision of a piston of hollow
- and light construction having a guide-way, preferably diametrically disposed therein, of cylindrical form and having members connecting its opposite ends disposed on both sides of such guide-way: a hollow piston so constructed as to permit the bearing or bearings of the operative shaft to extend into its interior and to entirely accommodate therein the cranked portion of this shaft; a piston and cross-head of a construction and arrangement permitting the operative shaft, if so required, to be supported in bearings on opposite sides of the machine, and to extend laterally on one or on both sides thereof: a piston having a transversely bored guide-way and admission ports or openings extending from the guide-way to the opposite ends of the piston, such admission ports or openings being alternately opened and closed by the cross-head as it reciprocates in the guide-way: a hollow cross-head adapted to hold oil or grease for lubricating purposes, and means for automatically lubricating the operative parts of the pump or compressor by a mechanical conveyor functioning to elevate lubricant from a chamber during the operation of the machine, and means for the effective distribution and circulation of the lubricant so elevated.
- Reference being had to the accompanying explanatory drawings:
- Figure 1 is a view in longitudinal section of a pump or compressor according to the invention and wherein the operative shaft extends laterally on one side only of the cylinder.
- Figure 2 is a view in transverse section taken on the line 2—2 in Figure 1.
- Figure 3 is a view in horizontal section of my improved pump or compressor, wherein the operative shaft extends on both sides of the cylinder.
- Figure 4 is a view in longitudinal section of the cylinder and operative parts of the pump or compressor shown in Figure 3.
- In these views the numeral 5 designates a pump cylinder and 6 a lateral bearing support projecting from the cylinder, preferably at or about the middle point of its length. This bearing support may project from one side only of the cylinder as illustrated by the Figure 2 construction, or alternatively, two bearing supports 6 in coaxial alignment with each other may be em-

ployed and extend on opposite sides of the cylinder as is shown in Figure 3. The cylinder 5 may have its ends furnished with detachable covers 7, or, if preferred, it may 5 be closed at one end by a cover integrally formed therewith and at its opposite end by a detachable cover 7.

Slidably fitted in the cylinder and adapted to reciprocate therein is a hollow piston 8, within which is a transversely extending member 9. This member 9 is preferably 10 tubular in section, integrally formed with the piston 8 and diametrically disposed therein. The interior of said member 9 is 15 bored cylindrically, thereby forming a guide-way 10 of cylindrical form extending diametrically through the piston and terminating in openings in the periphery thereof.

A slotted opening 11 is formed through 20 one side of the tubular member 9 and parallel to the axis thereof as shown in Figure 2, or slotted openings 11 are similarly formed through opposite sides thereof as shown in Figure 3. Slotted openings 12 25 are likewise made in the portions of the walls of the piston 8 contiguous to the openings 11, and these openings 12 are arranged with their longer axes parallel to the axis of the piston 8. Said openings 11 and 12 30 are symmetrically disposed about the central horizontal and vertical planes of the piston 8 as will be readily understood from Figures 1 and 4.

An operative shaft 13 furnished with 35 crank arm 14 and crank-pin 15 is rotatably mounted in bearings 16 housed in bearing supports 6, which are of sufficient internal 40 diameter to readily permit the crank-arm 14 to be passed therethrough. The openings 11 and 12 are likewise made of sufficient width 45 to permit the crank arm 14 and crank pin 15 being placed into position within the piston 8. When the operative shaft is placed in position the cranked portion thereof comprising arm 14 (Figure 1) or arms 14 (Figure 3) and crank pin 15 are entirely disposed within the piston 8.

The bearings 16 are extended through 50 the openings 12 and project into the interior of the piston 8, thereby effectively supporting the cranked portion of the operative shaft 13. Said openings 12 are made of sufficient length to ensure that their ends do not strike upon the bearings 16 during 55 the reciprocation of the piston 8.

The parts 17 of the walls of the piston 8 remaining between the openings 12 and the tubular member 9 serve to connect together the opposite ends of said piston. 60 The piston 8 is thereby rendered stronger and can be made more lightly than pistons of known construction wherein the side member facing the operative shaft is completely slotted through and the metal on the 65 side of the guide-way remote from the op-

erative shaft alone serves to connect together the opposite ends of the piston. The space between the tubular member 9 and the wall of the piston provides ample room for the crank arm 14 to rotate. This construction of piston, moreover, permits the crank shaft to be extended through the cylinder 5 and to be supported on both sides thereof, thereby rendering possible the compact arrangement which is illustrated in Figures 3 and 4.

Rotatably mounted on the crank pin 15 and slidably fitting said guide-way 10 is a cylindrical cross-head or die-block 18 which is carried around in a circular path by the 70 crank-pin 15 and restrained by the guide-way 10 reciprocates axially therein. This cross-head 18, when employed, with an overhung crank pin as illustrated in Figures 1 and 2, may be constructed of a single piece 85 of metal. If a crank-shaft as shown in Figures 3 and 4 be used, it is necessary to make said cross-head in two parts 19 and 20, to facilitate its assembly on the crank pin 15. In order to accurately align said cross-head 90 parts, one of them as 19 is furnished with spigots 21 accurately fitting recesses 22 formed in the other part 20. When the two parts 19 and 20 have been mounted upon the crank-pin 15 bolts 23 or like connecting 95 means are passed through said parts and securely fix them together.

The cross-head 18 in addition to effecting reciprocation of the piston 8 also functions as a slide valve for controlling the admission of fluid alternately to opposite ends 100 of the cylinder 5 which constitute the working chambers thereof. For this purpose conduits 24, preferably tubular in section and integrally formed with the piston 8, 105 extend between said tubular member 9 and the ends 25 of said piston and terminate at their inner ends in ports or openings 26 in the guide-way 10. These conduits may be located on opposite sides of the axis of 110 the piston 8 as shown in Figure 1, or they may be arranged co-axially therewith as illustrated in Figures 3 and 4.

Fluid is conveniently admitted to the cylinder 5 at some point disposed on the 115 transverse central plane thereof. Preferably it is caused to enter the cylinder 5 through an orifice 27 (see Figure 2) which by means of the slotted openings 12 communicates at all times directly with the interior of the 120 piston 8 and thereby with said ports 26 through the openings 11.

For some applications of the invention an orifice 28 may be conveniently arranged at the upper part of the cylinder 5 as is 125 shown in Figures 1 and 2 and a channel 29, (indicated by broken lines in Figure 2) provided to furnish means of communication between said orifice 28 and the opening 12 when the cross-head 18 occupies its 130

central uppermost position as shown in Figures 1 and 2.

Discharge valves 30 of approved construction are provided at opposite ends of the cylinder 5 and may conveniently be located in the covers 7 either centrally as shown in Figure 3, or at other approved points as illustrated in Figures 1 and 2. It will be understood that said valves 30 may, if desired, be mounted on the ends of the cylinder 5 at any convenient parts thereof.

In operation, the cross-head 18 reciprocates in the guide-way 10 thereby opening and closing the ports 26 and alternately admitting fluid to opposite ends of the cylinder 5. Movement of the cross-head is so timed that at each reversal of the motion of the piston 8 the conduit 24 leading to the working chamber of the cylinder 5 from which fluid has just been expelled is rapidly opened, and the other or opposite conduit 24 is with equal rapidity closed. During the stroke of the piston unrestricted flow is maintained into the chamber being filled with fluid, while leakage from the chamber being evacuated is prevented by the pressure between the cross-head 18 and said guide-way 10. When the pump or compressor is intended for use with air and non-corrosive gases and liquids this system of admitting fluid to the working chambers of the cylinder is preferred owing to the high efficiency thereby attained. In the event of corrosive fluids being transferred by the pump it is desirable that they should be prevented as much as is possible from contact with the operative parts. For this and like purposes the conduits 24 are dispensed with and suction valves 31 of any approved construction are fitted in the cylinder covers 7 as indicated by broken lines in Figure 1, or, if preferred, they may be located at convenient parts of the cylinder ends.

When the operative shaft 13 is located on one side only of the cylinder 5, as is illustrated in Figures 1 and 2, it is necessary to extend the bearing support 6 outwardly for some distance to obtain a bearing 16 of sufficient length for said shaft. The space below said bearing 16 is formed into a chamber 32 the lower part of which is employed as a container for lubricant. This chamber 32 extends below the cylinder 5 connecting with the central portion thereof as shown in Figures 1 and 2, and it is furnished with filler and drain plugs 33 and 34.

An endless chain conveyor 35 having its upper portion accommodated in a recess 36 formed in the bearing 16 is employed to elevate lubricant from the chamber 32. This chain is passed over the operative shaft 13 and is freely suspended therefrom. The

lower portion of the chain is suspended in the lubricant contained in said chamber 32. In operation the chain elevates lubricant to the recess 36 from which ducts 37 lead to an auxiliary reservoir 38 formed by reducing in diameter the central portion of said bearing 16. A vent 39 permits air to readily escape from said reservoir in order that the flow of lubricant into the latter will not be impeded. Holes 40 extending upwardly from the reservoir 38 supply lubricant to the operative shaft 13.

The reservoir 38 is maintained full of oil up to the level of the axis of the shaft 13. At this level holes 41 on opposite sides of the bearing 16 conduct excess lubricant to the inner end thereof. Some of the escaping oil passes through a hole 42 in the crank arm 14 and lubricates the crank pin 15. The remainder of the escaping oil falls into the interior of the piston 8 and passing through holes 43 lubricates the guide-way 10. The oil after lubricating the piston finally gravitates to the chamber 32 to be again elevated by the chain conveyor 35. In this manner a continuous circulation of lubricant is maintained whereby the operative parts of the pump are effectively lubricated.

In order that the chain conveyor 35 may be conveniently inserted in position an opening 44 is made in the outer end of the chamber 32. This opening 44 is closed by an extension 45 of a flange 46 with which said bearing 16 is furnished and by means of which the latter is held in position.

To assemble the operative parts of a pump of the construction illustrated by Figures 1 and 2, the cross-head 18 is placed in the piston 8 and the latter is brought into its middle position in the cylinder 5. The operative shaft 13 is passed through the bearing support 6 and the crank pin 15 is inserted into the cross-head 18. The bearing 16 is finally placed over the shaft 13 and is then pushed into the bearing support 6.

In some constructions of the invention, it may be necessary or desirable to make the length of the cross-head 18 greater than the diameter of the piston 8, in which case there is made in the cylinder 5 an aperture 47 of sufficient size to permit the cross-head being passed therethrough into the guide-way 10. When a two-part crosshead, as shown in Figure 4, is employed, it is necessary to furnish an aperture as 47 in the cylinder 5 to enable assembly of the cross-head parts being effected. These apertures 47 may be closed by detachable covers 48.

To assemble a pump wherein a two part cross-head is used, the lower member 20 of the latter having bolts 23 therein is placed in the guide-way 10. The piston 8 is brought into its central position in said cylinder 5, whereupon the operative shaft is inserted

into the bearing support 16 and is passed therethrough into the piston 8. The upper cross-head member 19 is then passed through the aperture 47 and is bolted to the lower member 20 and secured to the crank pin 15 as hereinbefore described.

In the construction of pump having centrally disposed conduits 24, it is necessary to provide the cross-head 18 with slotted openings 49 in order that the ports 26 may be open throughout the stroke of the piston 8. Similar slotted openings are employed when cross-heads 18 of considerable length are required for use as will be readily understood.

15 In Figure 1 the piston is assumed to be moving in the direction of the arrows 2. Fluid is then being expelled from the left hand end of the cylinder 5 and fluid is entering the right hand cylinder end through 20 the lower conduit 24. If the direction of rotation be reversed, the pump will not function unless the conduits 24 are brought into positions indicated by broken lines in Figure 1.

25 When the pump is required for operation in either direction a piston having openings 11 on each side of the guide-way is used. The crank-pin 15 may then be inserted into the guide-way 10 from either side and the 30 pump may be adjusted to run in either direction merely by turning the piston on its axis within the cylinder 5 to locate the conduits 24 in required relative positions as will be readily understood.

35 Similarly by axially turning the cross-head 18 the openings 49 therein can be adjusted into positions to function efficiently when the direction of movement of the piston 8 is reversed.

40 Pumps constructed as described have been found to be highly efficient when employed as compressors or vacuum pumps. For vacuum pumps or for compressors operating at low pressures the construction illustrated in Figures 1 and 2 is preferably employed. For compressors operating at higher pressures the construction shown in Figures 3 and 4 is preferred. In this construction the crank-shaft 13 is rigidly supported and is 45 well able to withstand the heavy stresses brought upon it in operation. The cylinder 5, covers 7, valves 30 and bearings 16 can be efficiently cooled by water-jacketing as indicated by the numeral 50. The entering air in its passage through the hollow piston effectively cools the same and contributes to the efficient operation of the machine. Openings 51 and 52 are provided through 50 which water respectively enters and flows away from the jacket 50.

When used as a vacuum pump or as a pump for liquids, the vessel to be exhausted or the source of supply is connected to the inlet orifice of the cylinder 5. In order to 65 prevent ingress of air along the operative

shaft 13, the outer end of the bearing 16 can be fitted with a cupped leather, or approved packing for the prevention of leakage.

If the cylinder 5 be provided with an aperture 47 and detachable cover 48 the upper part of said cross-head 18 may be used as a container for grease or like lubricant. This grease passes through holes 53 and lubricates the guideway 10 in an efficient manner.

The operative shaft 13 has been described as being supported in sleeve type bearings, but it is not restricted thereto as adjustable bearings may be fitted and for special purposes ball-bearings may be employed.

What I do claim is:—

1. In a pump or compressor, a cylinder, a hollow piston fitting the cylinder, to separate the cylinder into a pair of chambers one at each end of the piston, said piston comprising a cylinder longitudinally slotted in the side wall, a guide-way extending through the piston transversely of the slotted portion and longitudinally slotted, an operative shaft extending through the slotted portion of the piston having a crank to engage in the guide-way, a member rotatably mounted on the crank and reciprocable in the guide-way operative to reciprocate the piston by the rotation of the shaft, and means controlling the admission and expulsion of fluid to and from the cylinder during the reciprocation of the piston.

2. A pump or compressor having a cylinder, a hollow longitudinally slotted piston fitting the cylinder, a transverse slotted guide-way in the piston, a shaft extending through the piston and guide slots having a crank to engage in the guide, a cross-head rotatably mounted on the crank and slidably fitting the guide-way, and valves controlling the admission and expulsion of fluid to and from the cylinder.

3. A pump or compressor having a hollow piston, a cylindrically bored guide-way 110 diametrically disposed in said piston, slotted axial openings in said piston and in said guide-way, piston parts located on both sides of said guide-way and between said openings connecting the opposite ends of said 115 hollow piston, and conduits extending from said guide-way to the ends of said piston.

4. A pump or compressor having a cylinder, a hollow piston fitting the cylinder, a tubular guide-way transversely disposed in said piston, a rotatably mounted cross-head slidably fitting said guide-way, conduits extending from the guide-way to the opposite ends of the piston and coacting with said cross-head to control the admission of fluid to the cylinder, and discharge valves in said cylinder.

5. A pump or compressor having a cylinder, a hollow piston fitting the cylinder, a cylindrical guide-way formed in the pis-

- ton and diametrically disposed therein, centrally disposed slotted axial openings in said piston and in said guide-way, a bearing on the cylinder, an operative shaft in 5 the bearing, a crank on the operative shaft, a cylindrical cross-head rotatably mounted on the crank and slidably fitting the guide-way, and valves for the admission and expulsion of fluid to and from the cylinder.
- 10 6. A pump or compressor having a cylinder, a hollow piston fitting the cylinder, a cylindrical guide-way diametrically disposed in said piston, slotted axial openings in said piston and in said guide-way, a laterally projecting bearing support on the side of the cylinder, a bearing fitting said support, an operative shaft in the bearing, a crank on said shaft, a cross-head rotatably mounted on the crank and slidably 15 fitting the guide-way, an inlet orifice on said cylinder, conduits extending from the guide-way to the ends of the piston, and coacting with said cross-head to control the admission of fluid to the cylinder, and discharge valves in said cylinder.
7. A pump or compressor having a cylinder, a hollow piston fitting the cylinder, a guide-way in the piston, slotted axial openings in said piston and in said guide-way, an operative shaft extending through 20 said slotted openings and rotatably supported on opposite sides of the cylinder, a reciprocable element slidably fitted in said guide-way and rotatably mounted on said shaft, and means controlling the admission and expulsion of fluid to and from said cylinder.
8. A pump or compressor having a cylinder, a hollow piston in the cylinder, a guide-way diametrically disposed in the piston, slotted axial openings in said piston and in said guide-way, co-axially aligned bearing supports extending on opposite sides 25 of the cylinder, bearings fitted in said supports, an operative crank-shaft rotatably mounted in said bearings and extending transversely through said cylinder, a cross-head rotatably mounted on the crank-shaft and slidably fitted in said guide-way, an inlet orifice communicating with the cylinder, conduits extending from the guide-way to the ends of the piston and co-acting with said cross-head to control the admission of fluid to the cylinder, and discharge valves in said cylinder.
9. A pump or compressor having a cylinder, a hollow piston fitting the cylinder, a guide-way diametrically disposed in said piston, slotted axial openings in said piston and in said guide-way, co-axially aligned bearing supports formed integrally with and extending on opposite sides of the cylinder, bearings fitting said supports, an operative crank-shaft rotatably mounted in said bearings and extending transversely through 30 said cylinder, a two-part cross-head rotatably mounted on the crank-shaft and slidably fitted in said guide-way, means for aligning and means for connecting the two parts of the cross-head, an aperture in the cylinder, a detachable cover on the aperture, an orifice admitting fluid to the cylinder, conduits extending from said guide-way to the opposite ends of the piston and co-acting with said cross-head to control the admission of fluid to the working portions of the cylinder, and discharge valves in said cylinder.
10. A pump or compressor having a cylinder, a hollow piston in the cylinder, a transversely disposed guide-way in the piston, an operative shaft, a cranked member formed on the operative shaft and located in said piston, a bearing support formed integrally with said cylinder and of a size to permit of the passage therethrough of said cranked member, openings formed in said piston and in said guide-way extending longitudinally thereof permitting the entrance of said cranked member into said piston and guide way, and a bearing in said support 35 and extending through the slotted opening in said piston.
11. A pump or compressor having a cylinder, a hollow piston in the cylinder, a transversely disposed guide-way in the piston, an operative shaft, a cranked member formed on said shaft and located in said piston, co-axially aligned bearing supports positioned on opposite sides of said cylinder and of a size permitting the passage therethrough of said cranked member, axial openings formed in said piston and in said guide-way and made of dimensions to admit said cranked member, and bearings fitting said supports and extending 40 through the slotted openings in said piston.
12. A pump or compressor, having a cylinder, a hollow piston in the cylinder, a guide-way in the piston, a laterally extending bearing support on the cylinder, a lubricant chamber below said support, a bearing in said support, a crank-shaft in the bearing, an auxiliary reservoir in said bearing, means operated by the crank-shaft for elevating lubricant from said chamber to said reservoir, and means for distributing lubricant from said reservoir to said crank-shaft, to 45 said piston, and to said guide-way.
13. A pump or compressor having a cylinder, a hollow piston fitting the cylinder, a guide-way in the piston, a slotted axial opening in said piston, a laterally extending bearing support formed on the cylinder, a chamber for lubricant below said support and extending beneath said cylinder, a bearing fitting said support and extending through said axial opening into said piston, a crank-shaft in the bearing, an auxiliary reservoir in the bearing, a recess in said bearing, an endless chain depending from 50

8
said shaft and having its upper portion located in said recess, an opening in said chamber, a flange formed on said bearing and covering said opening, ducts extending from said recess to said reservoir, an air vent, holes connecting said reservoir with said crank-shaft, outflow holes between the reservoir and the end of the bearing within said piston, and holes connecting the interior of the piston with said guide-way.

14. A pump or compressor having a cylinder, a hollow piston in the cylinder, a guide-way in the piston, a rotatably mounted hollow cross-head slidably fitted in the 15 guide-way, holes in said cross-head, an aperture in said cylinder, and a cover on said aperture.

15. A pump or compressor having a cyl-

inder, a hollow piston in said cylinder, a guide-way in the piston, a rotatable operative element slidably fitted in said guide-way, a lubricant chamber, an endless conveyor elevating lubricant from said chamber, an auxiliary lubricant reservoir to which lubricant elevated by the conveyor from the 25 first lubricant chamber is delivered, and means for distributing lubricant from said latter reservoir to the operative parts of the pump.

In testimony whereof I affix my signature 30 in presence of two witnesses.

ARTHUR G. L. NEIGHBOUR.
